UNITED STATES PATENT OFFICE.

WILLIAM E. ANDRÉE, OF CHICAGO, ILLINOIS, ASSIGNOR TO THE AMERICAN LAUNDRY MACHINERY COMPANY, OF NORWOOD, OHIO, A CORPORATION OF OHIO.

KICK-OFF DEVICE FOR GARMENT-PRESSES.

1,311,546.

Specification of Letters Patent. Patented July 29, 1919.

Application filed November 1, 1917. Serial No. 199,857.

To all whom it may concern:

Be it known that I, WILLIAM E. ANDRÉE, citizen of the United States, residing at Chicago, in the county of Cook and State of Illinois, have invented certain new and useful Improvements in Kick-Off Devices for Garment-Presses, of which the following is a specification.

This invention relates to garment pressing machines, and more particularly to machines of this kind when operated in multiple. The invention is an improvement upon the construction described and claimed in a prior application of Chas. L. Braley for tandem attachment for ironing presses, filed August 24, 1916, Serial No. 116,696.

The object of the invention is to provide an improved construction for coupling or connecting together a plurality of garment pressing or ironing machines located adjacent to each other so as to be capable of operation by a single operator stepping from one machine to the other. More particularly the invention has for its object to provide direct coupling or connections between the pressure applying means or device of one machine and the releasing means or device of the other machine, so that the ordinary operation of one machine to apply pressure to the work will automatically kick off or release the other machine, and vice versa.

A further object of the invention is to generally improve the construction of the connections between the several pressing machines.

Further objects of the invention are in part obvious and in part will appear more in detail hereinafter.

The invention comprises the construction and arrangement of parts hereinafter described and claimed.

In the drawings Figure 1 is a perspective view illustrating two machines located side by side and coupled according to the invention; Fig. 2, is an end view thereof; Fig. 3 is a perspective view only partly indicating the machines themselves, and illustrating two coupled machines located at an angle of 90° to each other; and Fig. 4 is a similar view illustrating two coupled machines located at an angle of 180° to each other.

The invention may be applied with equal facility to any desired kind or type of pressing machine, the particular construction of said machine being wholly immaterial as

long as it embodies a treadle or other device for applying pressure to the goods to be pressed and a treadle or other device for opening the machine to release the goods from pressure. The pressing machine may be actuated either by muscular force of the operator or by suitable power mechanism controlled by the operator. For example, said machine may be of the construction shown in my prior application for garment press, filed March 22, 1916, Serial No. 85,908, although, for purposes of illustration Fig. 1 represents a power press of the same general form as the press of my prior application for garment press, filed June 7, 1916, Serial No. 102,296. Only a brief description of said press is therefore essential. The press shown comprises a suitable frame 1 carrying a stationary pressing bed 2 on which the goods to be pressed are laid and a hinged arm 3 carrying an upper pressing member or head 4 movable into pressing relation with the bed. Movement of said upper pressing member is produced by a pivoted treadle 5 connected by a suitable series of levers and links to the hinged arm 3 and also connected to close a suitable switch (not shown) for controlling a motor 7 which through power mechanism produces the final heavy pressure of the head upon the bed. The pressure treadle 5 projects outwardly from the front of the machine into convenient position for application of the foot of the operator. At one side of the pressure treadle is a release treadle 8 pivoted at 9 to the frame and provided on its inner end with a laterally extending yoke or projection 10 lying beneath the pressure treadle 5. Said release treadle may also be connected to the motor switch before referred to and close the same so as to cause the motor to produce opening movement of the press. When the pressure treadle is down and the press is held in pressing position, as shown at the right in Fig. 1, pressure on the kick-off treadle 8 lifts the pressure treadle or actuates said switch and opens the press.

According to the present invention at least two machines are associated in co-operating relation so that they are capable of being operated by a single operator stepping from one press to the other. Fig. 1 shows two identical machines A, B, of the character just described, located side by side and coupled or connected according to the present

invention. The connections between said machines are as follows:

The frames of the two machines are provided with brackets 12 carrying bearings to support a shaft 13 extending from machine to machine. On said shaft is a hollow tubular shaft 14 rotating in supports in other brackets 15 carried by the machine frames. Shaft 13 at one end is provided with a forwardly extending arm 16 pivotally connected at its outer end to a rod 17 extending down through an opening in the pressure treadle 5 of one machine, say machine A, and beneath said treadle being provided with a suitable abutment, such as a nut or nuts 18 threaded onto the end of the rod. The opposite end of shaft 13 is provided with a rearwardly extending arm 19 pivotally connected by a link 20 to the outer end 20 of a lever 21 having a toe portion 22 lying above the kick off treadle 8 of the other machine, say machine B.

The sleeve 14, at one end is provided with a forwardly extending arm 23 pivotally connected to a rod 24 similar to the rod 17 and likewise extending through an opening in the pressure treadle 5 of machine B beneath which it is provided with a head 26. The opposite end of sleeve 14 is provided with a rearwardly extending arm 27 connected by a link 28 to a lever 29 on machine A and similar in all respects to the lever 21.

Let us assume that the presses are in the position shown in Fig. 1 with press B closed and press A opened. The operator applies goods or a garment to the bed of press A and there arranges it in proper form to be pressed. He then applies his foot to the pressure treadle 5 of machine A and brings the head of said machine into pressing relation with its bed. The downward motion of treadle 5 takes up the lost motion between said treadle and head 18, finally moving said head downwardly and turning the shaft 13, so as to pull on the link 20 and thereby actuate the release treadle of machine B, which immediately opens. The operator then steps to machine B and supplies a garment to be pressed thereto. During this time the garment on machine A is under pressure and subject to the heat of the heated head and bed. When the garment on press B is properly arranged the operator depresses its pressure treadle, and final downward motion of the pressure treadle of said machine turns the tubular shaft 14 and actuates the release treadle of machine A. When the operator steps back to machine A he immediately removes the garment therefrom and applies a new garment.

It will be readily seen that with this arrangement the operator can readily manipulate the two machines in substantially the same time ordinarily required to operate a single machine, but nevertheless with a large

increase in the output. He is under no duty to actuate the release treadle of each machine, as the release of each machine is automatically caused by application of pressure to the other.

The two coupled machines need not be located side by side, as frequently it is desirable where space is limited to otherwise arrange the machines.

Fig. 3 shows another arrangement in which machines M and N are located at an angle of 90° to each other. On each machine are located brackets 30 and 31 supporting outer tubular shaft members 32 and inner solid shaft members 33 connected by proper arms, 80 links and levers to the pressure and release treadles of the two machines in the same manner as in Fig. 1. The two sets of shaft members however, are at an angle of 90° to each other. Their adjacent ends are therefore journaled in bearings in a sleeve 34 adjustable vertically on a vertical standard or support 35, whose base rests on the floor or other support. To connect the two coöperating inner shaft members 33, one of said members is provided with an arm working in a yoke 37 on an arm 38 carried by the other shaft member 33. Sleeves 32 are likewise connected by a plain arm 39 and yoke arm 40. This arrangement transmits the 95 motion of one shaft member 33 to its companion shaft member 33 and from one tubular shaft member 32 to its companion shaft member 32.

Fig. 4 shows an arrangement in which the two machines X and Y are at an angle of 180° to each other, or in other words, are face to face. This arrangement requires a vertical standard or support 41 located midway between and at one side of the two machines and carrying laterally extending rods or members 42 which in turn support bearing members 43 in which the ends of the coöperating inner and outer shaft members 44, 45 are journaled. These shaft members 110 it will be understood are connected to the pressure and release treadles of two machines in the manner before described. The tubular shaft members 45 are coöperatively connected by a link 47 pivotally connected 115 to arms 46 on said two shaft members, one of said arms extending downwardly and the other upwardly. The inner shaft members 44 are likewise connected by a link pivotally connected to two similar arms 49 on the two 120 shaft members.

It will be obvious that two machines can be located at other angles than 90° and 180° and by a proper arrangement of links and levers or other mechanism their inner and outer shaft members may be operatively connected.

What I claim is:—

1. Apparatus of the character described, comprising two pressing machines, each em- 130

bodying relatively movable pressing members, a treadle for producing relative pressing movement of said members, and a release treadle, and means operatively connecting the pressure treadle of one machine to the release treadle of the other.

2. Apparatus of the character described, comprising two pressing machines, each embodying relatively movable pressing members, a treadle for producing relative pressing movement of said members, and a release treadle, operating mechanism for the release treadle of one machine extending to the other machine and a lost motion connection 15 between the pressure treadle of the other machine and said mechanism.

3. Apparatus of the character described, comprising two pressing machines, each embodying relatively movable pressing members, a treadle for producing relative pressing movement of said members, and a release treadle, operating mechanism extend-

ing from the pressure treadle of the first machine to the release treadle of the second machine and including a shaft, and an operating connection extending from the pressure treadle of the second machine to the release treadle of the first machine and including a tubular shaft sleeve upon first named shaft.

4. Apparatus of the character described, comprising two pressing machines, each embodying relatively movable pressing members, a treadle for producing relative pressing movement of said members, and a release treadle, and inner and outer shaft members, one end of each being operatively connected respectively to the pressure and release treadle of one machine, and at their opposite ends being pivotally connected to the release and pressure treadles of the other machine.

In testimony whereof I affix my signature.

WILLIAM E. ANDRÉE.
